UNITED STATES PATENT OFFICE.

CHARLES E. SWETT, OF WEST ROXBURY, MASSACHUSETTS, ASSIGNOR TO UNITED STATES ENVELOPE COMPANY, OF SPRINGFIELD, MASSACHUSETTS, A CORPORATION OF MAINE.

PROCESS OF RENDERING PAPER TRANSPARENT.

Application filed May 18, 1922. Serial No. 562,030.

To all whom it may concern:

Be it known that I, CHARLES E. SWETT, a citizen of the United States, residing at West Roxbury, in the county of Suffolk and 5 Commonwealth of Massachusetts, have invented a new and useful Improvement in a Process of Rendering Paper Transparent, of which the following is a specification.

The present invention relates to improvements in the art of treating paper, for the purpose of rendering it transparent. The process is applicable, for instance, to the manufacture of window envelopes of the one piece type, i. e., an envelope in which 15 an integral part of the material is made pervious to light by treatment with a suitable substance of a resinous or similar nature.

The invention resides in a certain mode 20 of treatment adapted to decrease very materially the time required for completing the transparentizing operation and for bringing the treated blanks or sheets into condition for subsequent operations thereon, such as printing, stacking, folding and the like. In consequence of this, as hereinafter described, it is possible, by the use 25 of the invention, to coordinate, and to perform in a practically continuous manner, the several successive operations required 30 for the production of the finished articles.—without need for any substantial interruption in the entire manufacturing process from beginning to end.

It is well known that the impregnation 35 of paper with various suitable substances of a resinous or similar nature operates, to a greater or less degree, in making the material pervious to light, or transparent; and 40 it is also recognized that for permanence of result, the impregnating substance should remain in the paper in the form substantially of a solid. In the utilization of these principles, the practice, in general, 45 has been to use a solvent for the resinous or similar matter, the liquid mixture being applied to the paper and caused to penetrate its pores; thereafter, by driving off the solvent and drying the residue, the desired 50 result is obtained.

Heretofore, it has been deemed essential and indispensable to the above described process that the sheets or blanks of paper, following the application of the treating

liquid thereto, be subjected to a prolonged 55 period of heating, usually for upwards of an hour, the purpose being to render the solution thinner, thereby permitting its penetration into the paper and, by driving off the volatile matter, to procure, ultimately, the solidification and drying of the residue. Obviously, not until these actions have taken place is it possible to proceed 60 with the other operations to which the sheets or blanks are to be subjected. For 65 example, in the manufacture of one piece window envelopes, this transparentizing treatment has heretofore been available only as an independent preliminary operation, 70 separate and apart from the other manufacturing steps; the envelope blanks, after application thereto of the treating liquid, have to be spread out by hand on trays, to facilitate their disposal in a suitable oven or heating chamber, and then, following the prolonged heating of the treated blanks, they have to be handled a second time, in order to assemble them into stacks, preparatory 75 to their passage through an envelope folding machine.

I have discovered that the above described prolonged application of heat can be dispensed with in the process of transparentizing paper. In the accompanying drawing, the single figure represents, diagrammatically, one form of apparatus which may be used in putting my invention into effect, as hereinafter described. According 85 to my invention, the sheets or blanks, having received their imprints or coatings of the treating liquid, are subjected to alternate short periods of heating and cooling, the aggregate duration of which for the entire process need not, under ordinary circumstances, exceed two minutes,—in contrast with the much longer period, usually 90 an hour or more, that is required when the heating is uninterrupted.

The invention resides essentially in the above described mode of treatment, without 100 regard to the mechanism or apparatus employed for performing the same,—since it is obvious that the process is susceptible of utilization in a large variety of ways, as for instance, by causing the treated material, in its progress, either continuous or intermittent, towards those instrumentalities which convert it into the finished product, to pass

on an endless conveying belt 1, for example, through alternate hot and cold zones, the former being constituted, for example, by heated plates or coils, 2, 2, and the latter 5 either by the unheated intervening spaces or by blasts of air 3, 3 directed onto the material in the intervals between its subsections to heat.

The limits and proportions of time and 10 temperature, and also the number and duration of the alternate heating and cooling cycles will vary, for the different conditions and requirements that arise,—all of the 15 above being affected in greater or less degree by such factors as the thickness of the paper, and its condition as to moisture filling materials, sizing and the like, and also by the composition of the treating substance. In general, it is found advantageous 20 to give the heating periods a slightly longer duration than the alternate cooling periods, and also to subject the paper in said heating periods to somewhat higher temperatures than those that are reached 25 when prolonged and uninterrupted heating, according to previous known processes, is employed; this last can be done, without damage to the paper, because the heatings are of such short duration. This treatment, 30 giving accelerated impregnation to the paper, coupled with recurring opportunities for the condensation and solidification of the transparentizing substance, need only be continued for a very short time; its

culmination finds the sheets or blanks in condition for immediate further operations thereon,—the impregnated portions thereof having hardened and dried sufficiently to permit stacking of the sheets or blanks, without danger of sticking. As applied for 40 instance to the manufacture of one piece window envelopes, the invention, by eliminating the necessity for prolonged transparentizing treatment, permits said manufacture to be carried on in a substantially 45 continuous manner without undue delay or interruption in the progress of the envelope blanks through the successive steps of treating, drying, stacking and folding.

I claim:

1. In the art of rendering paper transparent by the application thereto of an impregnating substance, the improvement which consists in subjecting the paper to recurring alternate heating and cooling periods of short duration to obtain accelerated penetration and solidification of the impregnating substance.
2. In the art of rendering paper transparent, the improvement which consists in applying to the paper an impregnating substance, and heating the paper at intervals, alternately with exposures to atmospheric temperature, to obtain solidification of said impregnating substance.

Dated this 16th day of May, 1922.

CHARLES E. SWETT.
